UNITED STATES PATENT OFFICE.

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Application filed August 4, 1925. Serial No. 48,044.

To all whom it may concern:

Be it known that I, HENRY E. LEPPERT, a citizen of the United States of America, residing at New Britain, county of Hartford, State of Connecticut, have invented a new and useful Electric Switch, of which the following is a specification.

My invention relates particularly to snap switches of the so-called toggle or lever type. It is customary to mount these switches in boxes or receptacles from which the operating lever projects.

The main object of my present invention is to provide simple and inexpensive means for indicating whether the switch is on or off.

A more specific object is to provide a construction in which the indicator can be readily applied or removed when desired but in which the indicator is normally securely mounted.

Fig. 1 is a perspective view of an enclosed type switch embodying my invention.

Fig. 2 is a longitudinal sectional view showing details of the construction as applied to what is commonly termed a flush type switch.

Fig. 3 is a front view of a switch with the indicator applied but omitting the usual face plate or box cover.

Fig. 4 is a transverse sectional view showing the connection between the indicator and the operating lever and the method of removing the indicator.

Fig. 5 is a fragmentary front view of the yoke through which the operating lever projects and which serves as a support for the indicator.

Fig. 6 is a perspective view of the indicator slide, the slide being turned upside down so as to more clearly show the hook members.

In the preferred form the mechanism is provided with a yoke or strap member 8 which extends lengthwise at the front of an insulating block or body 9 which contains any suitable form of switch mechanism. This yoke may be conveniently secured in place by one or more screws 10 inserted from the rear as is customary in structures of this general character.

The switch is provided with an operating handle or lever 11 which is connected at the rear to the switch mechanism in any suit-

able manner (not shown) and projects at 55 the front through the slot 12 in the yoke 8. The lever 11 is oscillated up or down as required to operate the switch in the usual manner.

In the construction shown in Fig. 1 the 60 switch mechanism is mounted within a box or receptacle having a body 13 and a cover 14. The cover is provided with a slot 15 for the operating lever 11.

The indicator slide 16 is mounted on the 65 lever 11 and slides on the front of the yoke 8 between the guiding projections 17 and 8 between the guiding projections 17 and 8 behind the cover 14 or the face plate 14'.

This slide is preferably of thin sheet metal 70 in the form of a slightly bowed spring as 75 shown in Figs. 2 and 6. This slide is provided with rearwardly projecting hooks 18 which are adapted to be inserted through the notches 19 in the sides of the slot 12 of the yoke 8, in order to secure it in operative 75 position.

It would be obvious that this assembly or the reverse operation of separation could only be affected when the lever 11 is in its central position substantially at right angles 80 to the face plate. It would be understood of course that snap switches of this character are normally either on or off and the lever is never in the central position except when it is deliberately moved and held there. 85 Consequently the slide itself is always snapped past this central position and there is therefore no danger of the slide ever becoming accidentally detached even when the face plate is removed.

The face plate or cover is adapted to be secured to the yoke 8 in the usual manner as for instance by means of one or more screws 20. When this face plate is in position the slide 16 is of course prevented absolutely 95 from being detached. It would also be noted that this slide closes the slots 15 and 12 so that no foreign matter, dirt or insects can pass through the slot no matter whether the switch is on or off.

While I have shown the indicator as having the words "On" and "Off" to indicate the condition of the circuit it should be understood that I have used this expression merely as typical of any other means of indication such as the words "Light" or "Out" or light and dark colors as are sometimes used on such indicators.

It would also be understood that the indicators might be marked with luminous paint in any suitable manner.

Such a construction readily lends itself to variation from an indicating to a non-indicating type or vice versa or to a change in the character of indication by simply substituting one or another indicator or slide as may be desired.

10. I claim:

1. A snap switch comprising a yoke, an operating lever extending through said yoke, a slide having a hooked connection with said yoke and a loose connection with said lever.

2. A snap switch comprising a yoke, a lever extending through said yoke, a spring slide mounted on said lever and having hooks normally holding said slide to said yoke, said yoke having notches to permit disengagement of said slide from said yoke when in a certain position.

3. In a snap switch, a support having guide members, an operating lever extending through said support, a slide mounted on said support and guided thereby and having

interlocking connection with said lever and with said support to prevent disengagement except when said lever is in a certain definite position.

4. In a snap switch, a plate having a slot, a lever movable in said slot, an indicator mounted on said lever and covering said slot and having an interlocking engagement with said plate.

5. In a snap switch, a support, a face plate having a slot, an operating member extending through said slot, an indicating member mounted between said support and said face plate and detachably connected with said operating member and movable therewith and means of connection between said indicator and said support to normally prevent detachment of said indicator.

6. In a snap switch, a plate having a slot with a notch in the side of the slot intermediate its ends, an operating member extending through said slot and an indicator connected to said operating member and having a hook engaging said plate at the edge of said slot except at said notch.

HENRY E. LEPPERT.
